UNITED STATES PATENT OFFICE

2,272,814

VACUUM CLEANER

Carl W. Olson, Minneapolis, Minn.

Application July 15, 1940, Serial No. 345,618

4 Claims. (Cl. 15—8)

This invention relates to suction cleaning devices commonly known as vacuum cleaners, and its general object is to provide a cleaner of the electric driven vacuum or suction type which is constructed on a principle somewhat remote from that of the conventional cleaner, to not only increase the efficiency of the suction action to a maximum degree, with minimum consumption of current, but renders the cleaner practically noiseless. Those advantages are brought about by several important features among which is the provision of outlet means for the free passage of air from the suction fan and the elimination of the usual closed fabric dust bag, thus making it possible to materially reduce the speed of the fan, as in the conventional bag type cleaner the fan must rotate at a terrific rate of speed in order to provide sufficient suction to overcome the back pressure resulting from the use of the closed dust bag.

Another object is to provide a suction cleaner that includes a relatively small suction chamber directly communicating with a relatively large dust chamber or collector, and due to the size of the dust chamber, in comparison with that of the suction chamber, the dust laden air will expand when it enters the dust chamber, which results in reducing the velocity of the air to an extent, so that the dust will tend to settle or gravitate to the bottom of the dust collecting chamber, while the air is freely exhausted through outlet means in the form of screened openings.

A further object is to provide a suction cleaner that includes means in the path of the dust laden air from the suction chamber, to separate the dust from the air, so as to increase the gravitational action of the dust and to eliminate clogging of the screened openings, as the air is practically free from dust as it passes through the screens, and the separating means also decreases the velocity of the air and consequently noise.

A still further object is to provide a suction cleaner that includes an improved suction and blower unit, in that the suction chamber is provided with two laterally disposed inlet openings from the nozzle and the fan is of a squirrel cage type, as well as includes relatively wide vanes rotating about the fan motor, so as to not only cool the motor, but makes it possible for the fan and motor to take up minimum space.

Another object is to provide a suction cleaner that is simple in construction, inexpensive to manufacture, light in weight, shaped to facilitate its application below furniture and the like,

and is extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side elevation of the suction cleaner which forms the subject matter of the present invention.

Figure 2 is a sectional view taken approximately on line 2—2 of Figure 3, looking in the direction of the arrows.

Figure 3 is a sectional view taken approximately on line 3—3 of Figure 2, looking in the direction of the arrows.

Figure 4 is a sectional view taken approximately on line 4—4 of Figure 2, looking in the direction of the arrows.

Figure 5 is a sectional view taken approximately on line 5—5 of Figure 4, looking in the direction of the arrows.

Figure 6 is a sectional view taken approximately on line 6—6 of Figure 2, looking in the direction of the arrows.

Figure 7 is a sectional view taken approximately on line 7—7 of Figure 3, looking in the direction of the arrows.

Referring to the drawings in detail, it will be noted that my cleaner includes a relatively narrow elongated casing providing the body therefore and having front and top wall portions 1 and 2 respectively that are curved in streamline formation and a removable rear wall portion 3 curved accordingly to the bottom of the casing, as clearly shown in Figure 2. The front wall portion merges into an arcuate forward bottom wall portion 4 having formed on the rear thereof of a downwardly curved intermediate bottom wall portion 5, while the remaining portion of the bottom of the casing is open but is closed by a dust receiving receptacle in the form of a drawer 6 which will be later described.

Shaped to follow the marginal edges of the respective wall portions 1 to 5 inclusive, are flat side walls 7 detachably secured to said wall portions by screws, as shown, so that ready access can be had to the interior of the casing by removing either of the side walls. The said wall

portions are shown as having formed thereon ears 8 for receiving the screws, but they may have inturned flanges formed thereon having threaded openings for the screws. Detachably and pivotally secured to the side walls are the arms 9 of a yoke having a socket 10 therein, within which is secured a handle 11 which may of course carry the usual switch for controlling the motor and the usual bracket members for receiving the cord for the motor, as will be apparent.

Formed on and directed forwardly from the front wall portion 1 and at a downward inclination, is the inlet spout 12 of the head 13 of a nozzle, the head 13 being of the usual elongated inverted channel formation and mounted for rotation in the head is a cylindrical brush 14 driven from the motor in the usual manner. The head and casing are supported by caster wheels 15 in a manner whereby the head is disclosed in close proximity to the surface to be cleaned, as will be apparent upon inspection of Figure 2.

The arcuate forward bottom wall portion 4 is formed to extend into the casing, to provide a vertical partition 16 disposed transversely of the casing substantially midway its ends, as clearly shown in Figure 2. Formed on or otherwise secured to the wall portions 1, 2 and 4, as well as the partition 16, is a pair of longitudinally extending partitions 17 cooperating with the side walls 7 to provide laterally disposed air inlet chambers 18 having communication with the inlet spout 12 by openings 19 disposed in the front wall portion and the partitions 17 likewise cooperate with the partition 16 to provide a relatively small suction chamber 20 that directly communicates with a dust chamber 21 rearwardly of the partition 16 through the medium of a passage provided by an opening 22 in the partition 16 and by the upper rearwardly disposed extensions 23 of the partitions 17, as will be obvious upon inspection of Figure 2.

The dust chamber is of the full width of the casing, as shown in Figure 3, consequently the dust chamber has a much larger area than that of the suction chamber, so when the dust laden air leaves the suction chamber, it will tend to expand within the dust chamber and thereby lose its velocity so that the dust will gravitate therefrom, while the air will pass through outlet openings in the form of slots 24 arranged in the side walls 7 one above the other and longitudinally thereof, as best shown in Figure 1. The slots are covered with any suitable screening material 25, such as wire mesh, fabric, or the like.

The partitions 17 are provided with inlet openings 26 that register with each other and are of a size to take up the major portion thereof. Suitably secured to one side wall 7 is a motor 27 that extends through the opening 26 of the adjacent partition 17 for disposal within the suction chamber 20, as best shown in Figure 4, and secured to the motor armature shaft which extends through the opening 26 of the other partition, is a substantially semi-spherical hub member 28 of a fan which includes a ring 29 formed on and extending outwardly from the outer periphery of the hub member 28, for disposal in surrounding relation about the motor casing. Secured to the ring 29 and extending from opposite sides thereof are curved blades 30 providing vanes for the fan, and the ring 29 may be slotted and have the blades mounted

within the slots. In any event, the blades are of a length slightly shorter than the width of the suction chamber 20 and the fan is of a diameter slightly less than that of the openings 26.

The armature shaft has a pulley secured thereto, about which is trained a belt 31 that is likewise trained about the brush 14 for rotating the latter in the usual manner.

The dust receiving receptacle or drawer 6 is carried by the removable rear wall portion or closure 3 and is secured to and extends forwardly from the lower end of the portion 3 for closing the rear opening in the bottom of the casing, as best shown in Figure 2. The side walls 7 as well as the rear end of the downwardly curved intermediate bottom wall portion 5 are provided with grooves 33, the grooves of the side walls slidably receiving tongues 34 formed on the sides of the drawer 6, while the groove of the wall portion 5 receives a tongue 35 formed on the forward portion of the drawer, as clearly shown in Figures 2, 6 and 7. The removable rear wall portion or closure 3 has webs or flanges 36 secured thereto adjacent its side edges to be received within the casing, and the upper edge portion of the wall portion 3 is reduced as at 37 for disposal in overlapped association with the reduced edge portion of the top wall portion 2, as clearly shown in Figure 2, which likewise illustrates that the drawer 6 is further connected to the wall portion 3, by brace strips 38 secured to the webs 36 and the sides of the drawer. In order to facilitate the application and removal of the drawer, together with the wall portion or closure 3, the latter has secured thereto a handle 39.

Arranged in the dust chamber for disposal in the path of the dust laden air from the suction chamber, is a spiral strip 40 that is secured to the wall portion 3 to be carried thereby to facilitate cleaning the strip at the same time the dust is removed from the drawer 6, and the coils of the strip not only act in the capacity of reducing the velocity of dust laden air when it reaches the dust chamber, but also tends to separate the dust from the air, with the result it will be seen that the expanding air together with the coils of the strip 40 will cause the air to materially lose its velocity, and to an extent whereby the dust will settle or gravitate to and within the drawer 6.

I preferably provide strips 41 and 42 of rubber or the like secured to and disposed respectively about the drawer 6 and the open lower portion of the casing closed by the drawer, and arranged in a manner so that the strips will be disposed in overlapped association when the drawer is in place, as best shown in Figures 6 and 7, to provide a dust proof connection between the drawer and the casing.

From the above description and the disclosure in the drawings, it is believed that the operation of my cleaner will be obvious, but it might be mentioned that when it is in operation, the air currents produced by the fan and as indicated by the direction arrows in Figures 2 and 3 of the drawings, draw dirt, dust and foreign matter from the nozzle to the air inlet chambers 18 through the medium of the openings 19. From the chambers 18, the dust laden air is drawn through the openings 26 into the suction chamber 20, and thence is blown through the opening 22 and passageway provided by the extensions 23, for disposal within the dust chamber 21 and against the spiral strip 40 to be given a circular movement for retarding the velocity of the air,

as well as to separate the dust therefrom, thence the air free from foreign matter passes through the screened slots 24 to the atmosphere. It will therefor be seen that the air passes freely through my cleaner, and thereby the suction action is not retarded, which makes it possible to run the fan at a greatly reduced speed than that of the fan of a conventional closed bag type cleaner, due to the fact that the bag sets up a back pressure which requires the fan to be rotated at a terrific rate of speed in order to provide sufficient suction action. It will be further seen that the reduced fan speed, together with the decreased velocity of the air within the dust chamber, renders my cleaner practically noiseless, when considering the noise produced by the conventional cleaners.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A suction cleaner comprising a casing, an inlet nozzle secured to the casing, means dividing the casing into a pair of inlet chambers each opening into the nozzle, a relatively small suction chamber between the inlet chambers and opening upon opposite sides thereof into the inlet chambers, and a relatively large dust chamber opening into the suction chamber, said casing having screen closed outlet openings therein for direct communication of the dust chamber to the atmosphere, suction means within the suction chamber, spiral means within the dust chamber and disposed in the path of the dust laden air from the suction chamber for directing the same in as piral path to reduce the velocity thereof and for separating dust from the air, a removable wall portion for the casing, and a dust receiving receptacle slidably mounted in the casing for receiving the dust from the dust chamber and carried by said wall portion for removal therewith.

2. A suction cleaner comprising a casing, an inlet nozzle secured to the casing and extending forwardly therefrom at a downward inclination, a partition extending transversely in said casing and dividing the latter to provide a relatively large dust chamber in the rear of the casing, a pair of partitions extending longitudinally in said casing and forwardly from the transverse partition to the forward portion of the casing, said longitudinally extending partitions providing lateral inlet chambers and a relatively small suction chamber between the inlet chambers, said suction chamber opening on opposite sides into

the inlet chambers and the latter each opening into the nozzle, said transverse partition having an opening therein and providing direct communication between the suction and dust chambers, said casing having screen closed outlet openings therein for direct communication of the dust chamber to the atmosphere, suction means within the dust chamber for receiving the dust laden air from the suction chamber and being shaped to direct the air in a spiral path, a brush within the nozzle and driven by the suction means, and a removable dust receiving receptacle for the dust chamber.

15 3. A suction cleaner comprising a casing, an inlet nozzle secured to the casing, a partition extending transversely in said casing and dividing the latter to provide a relatively large dust chamber in the rear of the casing, a pair of partitions extending longitudinally in said casing and forwardly from the transverse partition, said longitudinally extending partitions providing lateral inlet chambers and a relatively small suction chamber between the inlet chambers, said longitudinally extending partitions having openings therein providing communication between the inlet chambers and the suction chamber and the inlet chambers having direct communication with the nozzle, said transverse partition having an opening therein providing direct communication between the suction and dust chambers, said casing having screen closed outlet openings therein for direct communication of the dust chamber to the atmosphere, suction means within the suction chamber, and a dust receiving drawer removably secured to the casing to underlie the dust chamber.

4. A suction cleaner comprising a casing including a removable rear wall portion, an inlet nozzle secured to the casing, means dividing the casing into a relatively small suction chamber having indirect communication with the nozzle and a relatively large dust chamber having direct communication with the suction chamber, side walls for the casing and having a plurality of superimposed screen covered slots therein providing outlet openings for the dust chamber, suction means within the suction chamber, a spiral strip having one end secured to the removable rear wall portion to be carried thereby, said strip being arranged in the path of dust laden air from the suction chamber for directing said air about the coils of the strip to separate the dust therefrom and to reduce its velocity, a dust receiving receptacle in the lower end of the dust chamber, said receptacle being detachably secured to the casing and fixed to the removable rear wall portion, and a handle secured to the removable rear wall portion.

CARL W. OLSON.
